UNITED STATES PATENT OFFICE.

ELMER E. WELSH, OF LAWRENCE, KANSAS.

SPIKE-EXTRACTOR.

SPECIFICATION forming part of Letters Patent No. 672,927, dated April 30, 1901.

Application filed December 31, 1900. Serial No. 41,725. (No model.)

To all whom it may concern:

Be it known that I, ELMER E. WELSH, a citizen of the United States of America, residing at Lawrence, in the county of Douglas and State of Kansas, have invented certain new and useful Improvements in Spike-Extractors; and I do hereby declare that the following is a full, clear, and exact description of the invention, such as will enable others to make and use the same, reference being had to the accompanying drawings, forming a part of this specification.

The objects of my invention are, first, to obtain a bite upon the spike in degrees without crushing strain; second, to obtain successive applications of the bite expeditiously, and, third, to provide an easy transmission of the leverage required to operate the jaws.

The invention consists in the novel construction and combination of parts, such as will be first fully described, and then specifically pointed out in the claims.

In the drawings, Figure 1 is a view in perspective of the novel spike-extractor. Fig. 2 is a rear enlarged view in detail of the spike-grasping jaws, also showing the jaw-operating lever and the bell-crank lever on the lower portion of the bar. Figs. 3 are views, in perspective, of the stationary and movable parts of the spike-grasping jaws disassociated. Fig. 4 is a detail view of portions of the separate operating and jaw-adjusting levers, showing the pivotal shoulder-and-socket connection of the jaw-operating lever. Fig. 5 is a detail view in perspective of the sleeve on the adjusting-lever.

Similar letters of reference indicate corresponding parts in all the figures of the drawings.

Referring to the drawings, A represents the main operating-lever of the spike-extractor, which consists of a flat bar of considerable length, so as to obtain the amount of leverage required to extract the spike, the forward and rear edges α and α' of the bar, from the jaws upwardly, inclining inwardly in a slight degree, decreasing the width of the bar at its upper end.

At the lower end of the main bar or lever A are the spike-grasping jaws B B'. The jaw B, which is stationary, consists of a body portion b , the front b^2 and rear portion b^3 of which

are in the plane of the front and rear edges α and α' of the lever or bar A. In width said body portion extends a short distance beyond the plane of the sides of said lever. The upper ends of the sides b^4 and b^4 of the body portion b are curved downwardly, and extend upwardly in the plane of the sides of the lever or bar A, and the forward portions of said upper ends are halved or cut away in a vertical direction. The lower end of the lever A is also halved at α^3 , and said halved parts are secured together by screw-bolts b^5 , thus enabling the body portion b to be readily detached from the lever A.

At the lower end of the body portion b is formed the spike-grasping part b^6 of the jaw, which is about one-half the thickness of the body portion b of the jaw, the inner side of which is nearly flat. The forward end of the part b^6 and the rear end b^7 extend beyond the plane of the front b^2 and rear b^3 of the body portion b , and the lower-rocking or under side b^8 of the part b^6 is formed in a single outwardly-curved line. On the inner side b^9 of the forward part b^6 of the jaw is an outwardly-curved depression extending from the upper edge of said part b^6 , which forms one of the spike-biting surfaces of the jaw.

In the rear side of the body portion b , directly above the part b^7 of the jaw, is a circular depression or socket b^9 , which extends about two-thirds the distance toward the forward side b^2 of the body portion b of the jaw, leaving the side of the socket exposed, and the shoulder b^{10} , which extends downwardly from the side b^4 of the body b of the jaw and partially incloses the socket. The lower part b^{12} of the movable jaw B' is the same as the part b^6 of jaw B secured in position, and upon the upper end of the said part b^{12} is a circular pivot or bearing b^{14} , extending about two-thirds the length of the jaw B and within the socket b^9 in the body b of the jaw B and fitting therein so as to move easily in the plane of oscillation. The outer side b^{15} of jaw B' extends upwardly a short distance at the point of connection of the bearing b^{14} and comes into contact with the shoulder b^{10} when the jaws B B' are opened to their widest extent. Through the body portion b of the jaw B and the side extends an opening b^{16} , which extends concentrically to the socket b^9 through

the bearing b^{14} , and through said opening extends a screw-bolt b^{17} , which has a head b^{18} at one end, and at the other end, upon said screw-threaded end, is a nut b^{19} , the head b^{18} being countersunk, as shown in the drawings.

With the rear end of the pivot or bearing b^{14} is connected rigidly the lower end c of the jaw-operating lever C , which extends upwardly in a curved line a short distance, and its upper end c' extended a slight distance beyond the plane of the side of the lever corresponding to that of the side b^4 of the body portion of the jaw b having the shoulder b^{10} , and in the upper end c' of said lever is a longitudinal slot c^2 .

D represents a bell-crank lever, which is arranged on lever or bar A , directly above the upper end of lever C , and is provided with a circular bearing or pivot d , which enters a socket d^2 in the rear edge a' of the lever or bar A . In the upper arm of the lever D is an opening d' . d^3 is a pivot on the lower arm which enters the slot c^2 in the upper end of lever C .

E is the power-transmitting and jaw-adjusting lever, which consists of a straight bar, the lower end of which lever is pivotally connected with the side of the bar A at a point about equidistant from the jaws B B' and the upper end of lever E .

Upon the lower end of lever A is an arm e , short in length and extending at right angles thereto, and upon the inner side of the lower end of the lever is a laterally-extended shoulder or bearing e' , circular in form, which extends within a socket e^2 , which extends a short distance within the side of the bar or lever A , as seen in detail in Fig. 4. In the outer end of the arm e is an opening e^3 , in which is inserted the upper bent portion e^4 of a rod e^5 , the lower bent end of which rod enters the opening d' in the upper arm of the bell-crank lever D .

Upon the same side of lever A with that of the lever E and a short distance upwardly from the pivotal point of connection of said lever with said lever A is a segment-plate F , which is arranged in position at right angles to bar A and close to the inner side of lever E . Said segment-plate is connected with the side of the bar A by means of a short downwardly-extended bar f , the lower end of which inclines inwardly and is secured by the screw f' . At each end of the segment-plate are outwardly-extended portions or stops f^2 , which limit the to-and-fro movements of the lever E .

In the upper curved edge of the segment-plate F are the notches f^3 , extending in series from one end of the segment-plate to the other. Extending loosely around the lever E , above the segment F , is a sleeve g , upon the inner side of which and extending from its lower edge toward bar A is a lateral extension g' , a portion g^2 of which also is bent downwardly at right angles in the plane of the inner side of the segment-plate F . Upon the under side of the lateral extension g' is a tooth g^3 , which

engages with the notches f^3 in the segment-plate. On the forward side of the sleeve g is a perforated extension or top g^4 , and upon the forward edge of the lever E , a short distance upwardly from the plane of the segment-plate, is an outwardly-extended lip g^5 , which is perforated. Through the perforated lip g^4 extends loosely a pin g^7 , upon the lower end of which is a head g^8 , the upper end of said pin extending through the perforation g^6 in lip g^5 and a short distance above said lip. Extending around the pin g^7 , between the lips g^4 g^5 , is a coiled spring g^9 . Upon the forward edge of the lever E , near its upper end, is a hand-lever G , at the lower end of which are the rear plates g^{12} and the short forwardly-extended arm g^{14} , which extend at right angles to the lever G , the plates g^{12} being pivotally connected with the lever E by the pivot g^{15} . In the outer end of the arm g^{14} is a perforation, in which is extended the upper end of a short rod g^{17} , the lower end of which rod is bent at right angles and extended through a perforation in the upper end of the pin g^7 .

In operation the bar or lever A is held in nearly an upright position with one hand, while the other hand grasps the lever E , the same hand extending to and grasping the hand-lever G , in which grasp the lever G at its upper end is thrown against the forward edge of the lever E , drawing up the sleeve g a short distance and releasing the tooth g^3 from the notches f^3 in the segment F . The lever E being moved forwardly against the forward stop f^2 operates the bell-crank lever D , drawing upon the upper arm of the lever, and consequently moving outwardly the upper end of the lever c' and opening the pin B' its full extent, the shoulders b^{10} b^{15} in the respective fixed and movable jaws coming into contact. The jaws B B' are then moved forward to admit the head or upper part of the spike to be drawn and which is seized between the parts b^x b^x on the forward part b^6 of each jaw. The grasp being retained on lever G the lever E is moved rearwardly in degrees until the bite of the jaws is sufficient to draw the spike, when the main lever A is moved rearwardly upon the curved bearing of the under side of the jaws, clutching the forward biting part of the jaws, and the spike is easily extracted. With the control of the lever E upon the jaws B B' repeated grasps of the jaws may be obtained with rapidity, thus increasing the leverage to meet the resistance of the spike.

It will be observed that the grasp of the jaws is in the lateral closing of the movable and fixed parts, so that no crushing strain occurs, and spikes or nails without heads and the parts of which are close in position to the tie are easily grasped and drawn from the tie. The construction of the novel spike-extractor affords convenient operation between closely-related track-rails and a longer reach obtained in the forward and backward movement of the lever A than in ordinary spike-

extractors and with a long or short purchase to grasp the spike and sufficient to do the work. The amount of leverage required is also more readily applied to the jaws than in 5 other forms of spike-extractors, thus affording an efficient and powerful implement.

Having fully described my invention, what I now claim as new, and desire to secure by Letters Patent, is—

- 10 1. In an implement for extracting spikes, &c., the combination with separate fixed and movable spike-grasping jaws of a main lever connected with the body of the fixed jaw and a vibrating lever connected with the movable 15 jaw an adjusting power-conveying lever pivotally connected at its lower end with the said main lever having an arm extending outwardly at an angle to said pivoted end and a connecting device connected with said arm 20 and also with the said vibrating lever on the movable jaw, a notched segment-plate connected with the main lever and adjustable interlocking devices on the adjusting-lever 25 engaging with said plate.
- 25 2. An implement for extracting spikes, &c., comprising separate fixed and movable spike-grasping jaws, a main operating-lever connected with the body of the fixed jaw, a separate vibrating lever connected with the movable 30 jaw having a slotted upper end a bell-crank lever on the main lever having one arm pivotally connected with the said vibrating lever, an adjusting power-conveying lever, pivotally connected at its lower end with 35 the main lever and having an arm extending outwardly from said pivoted end, a rod piv-

otally connected with said arm and also connected with the other arm of the bell-crank lever, a notched segment-plate on the main lever and adjustable interlocking devices on the 40 adjusting-lever engaging with said notched plate.

3. An implement for extracting spikes, &c., comprising separate fixed and movable spike-grasping jaws, a main operating-lever 45 connected with the body of the fixed jaw, a separate vibrating lever connected with the movable jaw having a slotted upper end, a bell-crank lever pivotally connected with the main lever and also with the slotted upper end of 50 the vibrating lever, an adjusting-lever pivotally connected at its lower end with the main lever and having an arm extending outwardly from said pivoted end, a rod pivotally connected with said arm and also with the 55 other arm of the bell-crank lever a notched segment-plate arranged between said adjusting and said main levers having a bar connecting said plate with the main lever, a sleeve upon the adjusting-lever having a tooth 60 engaging with the notches in said segment-plate; a hand-lever on the adjusting-lever having forwardly and rearwardly extended plates at its lower end one of which plates is pivotally connected with the adjusting-lever, 65 and a spring-retracted rod pivotally connected with the other plate and also with said sleeve.
